Primary Examiner — T Chase Nelson*Assistant Examiner* — Jonathan J. Han(57) **CLAIM**

The ornamental design for a featureless backstrap for a grip for firearms, as shown and described.

DESCRIPTION

FIG. 1 is a perspective view of a featureless backstrap of the invention, attached to a grip in broken lines;

FIG. 2 is a top view thereof;

FIG. 3 is a bottom view thereof;

FIG. 4 is a side view thereof;

FIG. 5 is another side view thereof; and,

FIG. 6 is a back end view thereof.

The broken lines used to show the unclaimed environment is for illustration purposes only and form no part of the claimed design.
